United States Patent Office

Des. 185,312
Patented May 26, 1959

185,312

STACKING CHAIR

Cecil Arthur Rassier, Erith, England

Application April 2, 1958, Serial No. 50,305

Term of patent 14 years

(Cl. D15—1)

FIG.1

FIG.2

Figure 1 shows an overhead three-quarter front perspective view of a stacking chair showing my new design; and

Figure 2 shows an overhead three-quarter rear perspective view from the other side.

I claim:

The ornamental design for a stacking chair, as shown.
